UNITED STATES PATENT OFFICE.

WEEDEN B. UNDERWOOD, OF ERIE, PENNSYLVANIA, ASSIGNOR TO AMERICAN STERILIZER COMPANY, OF ERIE, PENNSYLVANIA, A CORPORATION OF PENNSYLVANIA.

ELECTRIC HEATER.

1,128,554.

Specification of Letters Patent. Patented Feb. 16, 1915.

Application filed January 30, 1914. Serial No. 815,437.

To all whom it may concern:

Be it known that I, WEEDEN B. UNDERWOOD, a citizen of the United States, residing at Erie, in the county of Erie and State of Pennsylvania, have invented new and useful Improvements in Electric Heaters, of which the following is a specification:

This invention relates to electric heaters and consists in certain improvements in the construction thereof as will be hereinafter 10 fully described and pointed out in the claims.

The invention is illustrated in the accompanying drawings as follows:—

15 Figure 1 shows a central vertical section on the line 1—1 in Fig. 2. Fig. 2 a bottom view of the heater. Fig. 3 a diagrammatical view showing the method of connecting up the units with the terminals. Fig. 4 a 20 side elevation, partly in section, of one of the units. Fig. 5 a cross section of a unit on the line 5—5 in Fig. 4. Fig. 6 an edge view, partly in section of a unit.

1 marks the heater case. A head 2 is secured in the end of this case by the screws 25 3, a gasket 4 being used to make a tight joint, the heater here shown being especially designed for heating liquids, as water in sterilizing. The electrical connections are 30 mounted on the head 2 and it is, therefore, desirable to carry any drip there may be from the case 1 away from the terminals and connections and for this purpose I supply the lip 5 which extends beyond the head and 35 is positioned to carry any drip past the head. The unit cases 6 extend through perforations 7 in the head and are secured therein so as to make a complete closure in any desirable manner. The posts 8 extend downwardly 40 from the head 2 and the terminal supports 9—9 are secured to these posts. The terminal supports have the bowed centers 10, thus forming an opening 11 between them through which access may be had to the ends 45 of the units mounted in the head. The terminal supports have the centrally located terminals 12 and end terminals 13 and 14. The resistor leads 15 extend from the units to these terminals.

50 Fig. 3 shows in diagram the method of connecting up the leads with the terminals. In the heater shown there are eight units forming two duplicate series each having units *a*, *b*, *c* and *d*. The terminal 14 is connected with the units *a* and *b* by the leads

a' *b'*. The opposite sides of these units are connected with the terminal 12 by the leads *a*² *b*². The units *c* and *d* have one side connected with the terminal 13 by the leads *c'* *d'* and the opposite sides of said units are connected with the terminal 12 by the leads *c*² *d*². These units may by proper switches be used in varying combinations and arrangements so as to vary the capacity of the heater as desired. These variations are increased by mounting the two series together as this gives a nicer graduation as to heat capacities. By bowing the terminal supports access is given to the leads 15 through the opening 11 and these leads can be brought to the terminals arranged on the sides of the opening. Furthermore, if the head is circular as indicated in Figs. 1 and 2 this arrangement permits of as small a head as possible with a larger terminal. By spacing the terminal supports from the heads the screws 3 can be brought under the terminal supports (see Fig. 2) where necessary thus decreasing the size of the head.

55 The detail construction of the units is shown in Figs. 4, 5 and 6. An insulating piece 16 is provided with a series of slots 17 extending inwardly from its edge. The resistor 18 is wound on this insulating core extending from slot to slot. This is a common method of winding such resistors. Two of such resistor coils are arranged in each unit, the insulating strip 19 being arranged between the coils. Insulating strips 20 are arranged outside the coils and next the case 6.

60 Considerable difficulty has been experienced heretofore in preventing excessive heating at the point where the resistor extensions connect with the leads. One of the 95 principal objects of my invention is to correct this difficulty. Two resistor coils are connected by the connector lead 21. This is in the form of metal ribbon and is bent over forming a U-shaped strip. The ends are 100 carried under the resistor coils and between the outer wraps of the resistor coil and the insulating core. This lead extends under a plurality of these wraps and one of the desirable features of my invention is that this can be varied by actual test so as to give to the resistor just the resistance desired. The ends 21^a of the connector lead 21 are bent back upon the lead itself and woven under and over the wraps of the resistor as clearly 110

shown in Fig. 6. The unit so formed is then subjected to pressure so as to bring the connector lead into intimate contact with the leads of the resistor. Furthermore, after the 5 case 6 is put in place it is subjected to pressure so that there is a continued pressure exerted by the case on the unit holding the connector leads in close contact with the wraps of the resistor. The terminal leads 15 are 10 cured in the unit in the same manner as the connector leads 21, that is to say the terminal lead 15 is carried under a series of wraps of the resistor and the ends 15^a turned back and woven under and over the wraps of the resistor as clearly shown in Fig. 6 thus securing 15 the terminal lead in place and insuring pressure contact. This is made more certain by subjecting the case 6 to pressure after the unit is in place so as to have the case 6 exert 20 pressure on the lead 15 just as in the case of the connector leads. The resistance of the resistor may be varied either by the connector lead or terminal lead as may be more convenient. It is desirable, however, to have 25 both leads engage a plurality of wraps of the resistor.

What I claim as new is:—

1. In an electric heater, the combination of a resistor having a series of transverse portions; and a resistor lead woven into the resistor and engaging a plurality of transverse portions.
2. In an electric heater, the combination of a resistor having a series of transverse portions; and a resistor lead extending past a plurality of said transverse portions and having its end bent back upon itself and woven into said transverse portions of the resistor.
3. In an electric heater, the combination

of two resistor coils, the coils being adjacent to each other; and a connector lead between the coils, said lead being woven into each coil and forming an electrical contact therewith.

45

4. In an electric heater, the combination of a resistor having a series of transverse portions; a resistor lead engaging a plurality of said transverse portions; and a unit case arranged over said resistor and lead 50 and exerting pressure thereon to effect pressure contact between the resistor and lead.

5. In an electric heater, the combination of a heater head in which two series of heater units are mounted; bowed terminal 55 supports carried by the head and having an opening between them; terminals on said supports; and leads from said terminals accessible through said opening.

6. In an electric heater, the combination 60 of a heater head in which a series of units are mounted; terminal supports carried by the head and spaced therefrom; a heater case in which the head is mounted; and screws for securing the head to the case. 65

7. In an electric heater, the combination of electric units; a head in which said units are mounted; a terminal on the head in which the units are mounted; a heater case to which the head is secured, said case having a lip extending past the head for carrying the drip away from the head. 70

In testimony whereof I have hereunto set my hand in the presence of two subscribing witnesses.

WEEDEN B. UNDERWOOD.
